UNITED STATES PATENT OFFICE.

FREDRICK H. C. MEY, OF BUFFALO, NEW YORK.

CONVEYER.

SPECIFICATION forming part of Letters Patent No. 408,733, dated August 13, 1889.

Application filed September 3, 1888. Serial No. 284,460. (No model.)

To all whom it may concern:

Be it known that I, FREDRICK H. C. MEY, of the city of Buffalo, in the county of Erie and State of New York, have invented new 5 and useful Improvements in Conveyers, of which the following is a specification.

This invention relates to that class of conveyers which are employed more especially for transferring coal from the coal yard or 10 dock to cars or vessels, and which consist of an endless belt which is provided with an inclined portion, whereby the coal is elevated to the head of an inclined chute or delivery-conveyer, which conducts the material into 15 the hold of the vessel or into the cars.

The object of my invention is to construct the conveyer in such a manner that its inclined or elevated portion can be shifted or adjusted to accommodate the location of the 20 delivery-chute and the vessel, as circumstances may require.

The invention consists of the improvements which will be hereinafter fully described, and pointed out in the claims.

25 In the accompanying drawings, consisting of two sheets, Figure 1 is a longitudinal section of my improved conveyer. Fig. 2 is a sectional top plan view thereof. Fig. 3 is a transverse section of the conveyer, taken 30 through the tightener mechanism, on an enlarged scale. Fig. 4 is a fragmentary sectional elevation of the lower portion of the carriage upon which the tightener mechanism is mounted.

35 Like letters of reference refer to like parts in the several figures.

A represents the longitudinal base-rails of the conveyer.

B represents the endless conveyer, which 40 is composed of transverse slats *b*, secured with their ends to endless chains *b'*, and provided with overlapping side pieces *b''*, whereby the coal is prevented from falling over the sides of the conveyer.

45 C C' represent the main sprocket-wheels, around which the conveyer-chains *b'* run, and which are journaled at the upper ends of standards C² C³, arranged at opposite ends of the base-rails A. The intermediate up- 50 per portions of the conveyer are supported by sprocket-wheels *d*, which are mounted in

standards D D, secured to the base-rails A, and the intermediate lower portions of the conveyer are supported upon sprocket-wheels *d'*.

E represents an elevated tightener-frame, 55 in which are mounted a series of sprocket-wheels *e e' e''*, around which the upper portion of the conveyer runs. This tightener-frame is rectangular in form, and consists of side pieces *f f'* and round connecting-rods *f'' f''' f'''*, secured with their ends to the side pieces *f f'*, and upon which the sprocket-wheels *e e' e''* turn.

G represents a carriage or movable support, upon which the tightener-frame E is 65 mounted, and whereby the same is shifted toward one or the other end of the conveyer. The tightener-frame is journaled in the carriage G by means of trunnions *g g*, formed on the side pieces of the tightener-frame and arranged in bearings *g'*, formed in upward extensions or standards G' of the carriage. The tightener-frame E is journaled in the carriage at or near its center, and the sprocket-wheels *e e''* are arranged on opposite sides of 70 the pivots of the frame, while the wheels *e'* are arranged between said wheels. The carriage G is supported upon grooved rollers *h*, journaled in the lower end of the carriage-frame and running upon longitudinal tracks 75 *i*, secured to the upper side of the base-rails A.

j j represent detent-pawl pivoted to the lower end of the tightener-frame E and engaging with the curved ratchet-bars *J*, secured to the inner sides of the standards G' 85 of the carriage. These pawls hold the tightener-frame in position after the same has been swung on its pivots to tighten the conveyer.

G² represents a hand-wheel secured to one 90 of the trunnions *g* of the tightener-frame E, and whereby the latter is turned.

The endless conveyer runs from the sprocket-wheels C upwardly around the upper sprocket-wheels *e*, to form the elevating- 95 incline K, thence around the inner sides of the wheels *e' e''*, and thence around the main sprocket-wheels C' and back to the wheels C. The inclined chute, which is arranged underneath the overhanging upper portion of the incline K, and which delivers the coal to the 100 vessel or car, is shown by dotted lines in Fig.

- 1 at L. Upon releasing the pawls *j*, the tightener-frame can be swung into the proper position to loosen the conveyer, and the carriage with the tightener-frame can be moved back and forth between the main sprocket-wheels C C', to change the position of the incline K to suit the location of the coal or the vessel or car. When the carriage has been properly placed, the conveyer is tightened by swinging the tightener-frame in the proper direction to move the upper sprocket-wheels *e* away from the stationary sprocket-wheels C and the lower sprocket-wheels *e*' away from the stationary sprocket-wheels C', as represented in Fig. 1. 15 In this manner two bights or bends are formed in the upper portion of the conveyer, which are drawn in opposite directions by the upper and lower sprocket-wheels *e* *e*' in tightening the conveyer.
- 20 The inclined portion K of the conveyer is supported by sprocket-wheels *m*, which are mounted in brackets M, secured to the carriage G. The coal is dumped or shoveled upon the horizontal front portion of the conveyer at the foot of the incline K, carried upward by the latter and discharged upon the head of the inclined chute L, which latter conveys it into the vessel or car. Instead of the inclined chute, a supplementary conveyer 25 may be employed for conveying the coal from the head of the incline K to the vessel or car. It is obvious that the conveyer may be used for conveying grain and other material as well as coal.
- 30 I claim as my invention—
- 35 1. The combination, with the endless conveyer adapted to run around guide or sprocket wheels mounted in stationary supports, of a carriage, an elevated tightener-frame pivoted 40 at or near its center to said carriage, and

guide or sprocket wheels journaled at opposite ends of said tightener-frame, around which the upper portion of the endless conveyer runs, substantially as set forth.

2. The combination, with the endless conveyer adapted to run around guide or sprocket wheels mounted in stationary supports, of a carriage G, a swinging tightener-frame E, mounted on said carriage, and guide or sprocket wheels *e* *e*' *e*', arranged in said tightener-frame, substantially as set forth. 45

3. The combination, with the endless conveyer adapted to run around guide or sprocket wheels mounted in stationary supports, of a carriage, an elevated tightener-frame pivoted 55 at or near its center to said carriage, guide or sprocket wheels journaled at opposite ends of said tightener-frame, around which the upper portion of the endless conveyer runs, and means whereby said tightener-frame is held 60 in position after being adjusted, substantially as set forth.

4. The combination, with the endless conveyer adapted to run around guide or sprocket wheels mounted in stationary supports, of a carriage, an elevated tightener-frame pivoted 65 at or near its center to said carriage, guide or sprocket wheels journaled at opposite ends of said tightener-frame, around which the upper portion of the endless conveyer runs, and a pawl and ratchet, whereby said tightener-frame is held in position after being adjusted, 70 substantially as set forth.

Witness my hand this 16th day of August, 1888.

FREDRICK H. C. MEY.
